B. BERNSTEIN

CAP AND HOLDING DEVICE FOR OIL CANS

Filed Aug. 9, 1923

INVENTOR

Baruch Bernstein

BY

A. M. Martell

ATTORNEY.

UNITED STATES PATENT OFFICE.

BARUCH BERNSTEIN, OF HOLLYWOOD, CALIFORNIA; NOW BY JUDICIAL CHANGE OF NAME BURRIS BURNS.

CAP AND HOLDING DEVICE FOR OIL CANS.

Application filed August 9, 1923. Serial No. 656,609.

To all whom it may concern:

Be it known that I, BARUCH BERNSTEIN, a citizen of the United States, residing at Hollywood, in the county of Los Angeles and State of California, have invented new and useful Improvements in Cap and Holding Devices for Oil Cans, of which the following is a specification.

My invention relates to stoppers or caps for oil cans, and the general object thereof is to provide a cap holding device for holding the cap over the end of the spout of the oil can and closing said spout when the can is not in use, and for holding said cap on the can out of the way of the user of the can when the cap is removed from the spout so that the can may be used.

Other objects and advantages will appear hereinafter and while I show herewith and will describe a preferred form of construction, I desire to be understood that I do not limit my invention to such preferred form but that various changes and adaptations may be made therein without departing 25 from the spirit of my invention as herein-after claimed.

Referring to the drawing:

Fig. 1 is an elevation of an oil can embodying my invention, with the cap held by my invention on the spout of the can, closing said spout.

Fig. 2 is a view similar to Fig. 1 with the cap removed from the spout and held by my invention on the can receptacle out of the way of the user of the can.

Fig. 3 is a plan view of my invention with the cap shown partly in section.

In the drawing 1 indicates an oil receptacle and 2 a spout of an oil can, said receptacle being formed with a threaded mouth 3 in which the base 4 of said spout is screw seated.

My invention comprises a wire yoke 5, and a spring 6 connected at one end by a coupling 7 to said yoke and at its other end to a cap 8 by a coupling 9 and eye 10. The

yoke 5 is bent and twisted intermediate its ends into an eye 11. The coupling 7 comprises a single piece of wire bent at one end into a hook 12, which engages the eye 11 and at its other end into a hook 13, which engages a hook 14 on one end of the spring 6. The coupling 9 comprises a single piece of wire bent at one end into a hook 15, which engages a hook 16 on the other end of said spring, and at its other end into a hook 17, which engages the eye 10, which eye is formed with a yoke 18, which embraces the cap 8 and its ends are twisted together as at 19, whereby the cap is held securely by said yoke.

The yoke 5 embraces the mouth 3 and its ends are twisted together as at 20, whereby said yoke is held securely on said mouth. The cap 8 may be of cork or other suitable material and has a conical bore 21, which receives the upper end of the spout 2, whereby the cap fits on said end of said spout and closes the same, in which position the spring 6 is expanded and the cap is held by said spring firmly on the end of the spout, as shown in Fig. 1.

When the cap 8 is removed from the end of the spout the spring 6 may be stretched around the mouth 3 of the can, the hook 17 of coupling 9 engages with the eye 11 as shown in Fig. 2, whereby my device is held on the can out of the way, so that the can may be used for oiling.

I claim as my invention:

In combination with an oil can, a cap, a yoke secured around the mouth of the can and formed with an eye, a spring, means connecting said spring at one end to said eye, a coupling connecting the other end of said spring to said cap, said spring being adapted to hold said cap on said spout to close the spout and adapted to be stretched around said mouth and said coupling hooked in said eye to hold the cap when removed from the spout on the can out of the way.

BARUCH BERNSTEIN.
